UNITED STATES PATENT OFFICE

149,740

DESIGN FOR A MAGAZINE RACK

Lloyd S. Crain, Evanston, Ill.

Application March 29, 1946, Serial No. 128,077

Term of patent 3½ years

(Cl. D33—2)

To all whom it may concern:

Be it known that I, Lloyd S. Crain, a citizen of the United States of America and a resident of Evanston, county of Cook, and State of Illinois, have invented a new original, and ornamental Design for a Magazine Rack, of which the following is a specification, reference being had to the accompanying drawing, forming a part thereof.

In the drawing:

Fig. 1 is an end elevational view of a magazine rack showing my new design;

Fig. 2 is a side elevational view thereof;

Fig. 3 is a top plan view thereof; and

Fig. 4 is a perspective view thereof.

I claim:

The ornamental design for a magazine rack, substantially as shown.

LLOYD S. CRAIN.
